Primary Examiner — Susan Moon Lee*(74) Attorney, Agent, or Firm* — Robert J. Veal(57) **CLAIM**

The ornamental design for a bird feeder, as shown and described.

DESCRIPTION

FIG. 1 is a first top perspective view of the bird feeder;
FIG. 2 is a front view of the bird feeder;
FIG. 3 is a rear view of the bird feeder;
FIG. 4 is a first side view of the bird feeder;
FIG. 5 is a second side view of the bird feeder;
FIG. 6 is top view of the bird feeder;
FIG. 7 is a bottom view of the bird feeder;
FIG. 8 is a first bottom perspective view of the bird feeder;
FIG. 9 is a second bottom perspective view of the bird feeder;
FIG. 10 is a third bottom perspective view of the bird feeder;
FIG. 11 is a fourth bottom perspective view of the bird feeder;
FIG. 12 is a second top perspective view of the bird feeder;
and,
FIG. 13 is a third top perspective view of the bird feeder.
